PAPER FEED TENSION MECHANISM

Arthur William Harries, Twickenham, England,
assignor to Lynton-Brooke Company Limited,
London, England

Application December 2, 1932, Serial No. 645,487
In Great Britain February 1, 1932

6 Claims. (Cl. 101—228)

This invention relates to tensioning devices for the feeding of sheets of paper in web form through printing machines in which the feed to the impression cylinder is intermittent, the rotation of 5 the impression cylinder being divided into printing and non-printing periods and the feed of the paper ceasing during the non-printing period.

According to the present invention two, or more, 10 flexible arms are adapted to bear against the web where it engages a guide roller so as to place a tension during the printing operation on the stretch of paper passing to the impression cylinder from the roller, these tension arms being swung clear of the web at the end of each printing 15 operation, a second tension device comprising rollers carried on a swinging frame being adapted to fall onto and to take up the slack in the web and place a tension on it during the non-printing period.

In the accompanying drawings in which similar reference characters relate to like parts in all the figures:—

Figure 1 is a general view of a rotary printing machine with an intermittent paper feed and 25 provided with tension devices constructed according to the invention.

Figure 2 is an elevation to a larger scale of the tension mechanism.

Figure 3 is a plan view of Figure 2.

Figure 4 an elevation similar to Figure 2 but showing the parts in another position and

Figure 5 a partial section on the line A—B Figure 4.

The impression cylinder is shown at *c*, being 35 driven by the intermediate shaft *d* from the motor *e*, the paper feed roller shaft at *f* and the web of paper fed through the machine at *g*. Mounted in bearings *h* on the side frames *i* of the machine is a guide roller *k* from which the stretch 40 of paper *g'* passes to the impression cylinder *c* and disposed below the roller *k* is a shaft *m* that is rotatively carried in the frames *i* and on which are mounted a pair of flexible tension arms *n*. The shaft *m* is extended at both ends beyond 45 the frames *i* and on one such extended end is fixed a bar *o* to which is connected the rod *p* which is actuated by the cam *q* mounted on the impression cylinder shaft *r*. A bar *s* with an anchoring spring *t* is fixed to the other extended 50 end of the shaft *m*.

The cam *q* is so shaped and its operation so timed that when the printing operation commences the rod *p* by the operation of the cam *q* and through the link rod or bar *o* rotates the 55 shaft *m* so that the arms *n* are brought up against

the stretch of paper *g'* where it engages the guide roller *k* as shown in Figure 4, the bar *s* being also swung over and the spring *t* compressed, the stop *u* limiting the movement. Tension is thus placed on the stretch of paper *g'* during the printing operation and at the end of same the cam *q* acts on the rod *p* to swing the arms *n* through the bar *o* and by rotation of the shaft *m* back to their former position clear of the web as

5

10

The swinging tension frame *x* comprises the side bars *v* that are of curved formation as shown and are pivotally mounted at their rear ends on the shaft *w* carried in the side frames *i* so that the frame *x* can swing freely up and down, the upward movement of the frame being effected by the cam *y* on the shaft *z* operating the rod *z* connected to the rear end of one of the side bars *v*, but it falls into its lower position by gravity.

A stationary paper guide roller *2* is fixed on 20 the side frames *i* towards the rear of the frame *x* and a front tension bar *3*, that co-operates with the two bars *4* and *5* mounted in the side bars *v* towards the front of the frame *x* to place a tension on the web, is carried by the guide hangers 25 *6* fixed on the side frames *i*. Mounted on the rod *7* rotatably carried in the side frames *i* are a pair of resilient blades *8* and on one of the outer extended ends of the rod *7* is fixed a bar *9* with an anchoring spring *10* that maintains 30 the bar *9* normally against the stop *11* and thereby holds the blades *8* in the position shown in Figure 4.

At the end of the printing operation when the arms *n* are swung clear of the web (Figure 2) 35 the tension frame *x* falls automatically, the shape and operation of the cam *y* permitting, into the position shown in this figure whereby the paper web *g* allowed during the printing operation to sag between the rollers *k* and *2* (Figure 4) 40 is drawn taut by the three bars *4*, *3*, and *5* and is also held by the blades *8* which are depressed by the bar *5* and bear against the web where it is engaged by this bar.

Immediately the printing operation commences 45 the frame *x* is raised by the cam *y* acting through the rod *z* to its former position shown in Figure 4, the hanger *6* limiting the upward movement, and the arms *n* are brought up against the web *g'* as previously described.

Thus it will be seen that the tension arms *n* and the tension frame *x* act alternately to keep the stretch of paper *g'* between the guide roller *k* and the impression cylinder *c* taut during the printing operation and to take up the accumu- 55

lated slack in the web *g* between this roller *k* and the next guide roller *2* during the non-printing period.

It will be obvious that the tension devices described may also be employed in connection with machines of the platen type where there is an intermittent paper feed.

What I claim is:—

1. In combination, a rotary web printing machine, comprising an impression cylinder, a guide roller adjacent said cylinder, a second guide roller disposed between said first roller and the source of web supply, a tensioning device adapted to engage said web where the web engages said first roller during the printing period to keep the stretch of web between the first roller and said cylinder taut, and a second tensioning device adapted to engage said web at a point between said guide rollers during the non-printing period to take up the slack in the stretch of web between said rollers.
2. In combination, a rotary web printing machine, comprising an impression cylinder, a guide roller adjacent said cylinder, a second guide roller interposed between said source of web supply and the first roller, a tensioning device including a plurality of flexible arms adapted to bear against the web where it engages said first roller to place a tension during the printing period on the stretch of web passing from said first roller to the cylinder, cam operated means for swinging said arms clear of the web at the end of each printing period, a second tensioning means including a swinging frame and a plurality of bars on said frame adapted to fall against said web between said rollers during the non-printing period to place a tension upon said web and thereby take up the slack in said web between said rollers, and cam operated means for moving said frame and bars away from said web at the end of each non-printing period.
3. In combination, a web printing machine

comprising an impression cylinder, a pair of tensioning devices both located at one side of the impression cylinder, means for moving one of said tensioning devices against the web during the printing period and means for moving the other of said tensioning devices against the web during the non-printing period, the first tensioning device engaging the web at a point closer to the impression cylinder than that at which the second tensioning device engages the web.

4. A tensioning device for the web of paper fed through a printing machine comprising web tensioning means, means engaging said web tensioning means for operating said tensioning means only at predetermined intervals, a second web tensioning means engaging said web at a point different from that at which said first mentioned tensioning means engages said web, and means for operating said second web tensioning means only at predetermined intervals not coincident with said first mentioned intervals.

5. A tensioning device for the web of paper fed through a printing machine comprising web tensioning means, means engaging said web tensioning means for operating said tensioning means only during the printing period, a second web tensioning means engaging said web at a point different from that at which said first mentioned tensioning means engages said web, and means for operating said second tensioning means only during the non-printing period.

6. A tensioning device for the web of paper fed through a printing machine comprising web tensioning means, means engaging said web tensioning means for operating said tensioning means only during the printing period, a second tensioning means engaging said web at a point different from that at which said first mentioned tensioning means engages said web, and means for operating said second web tensioning means only during the non-printing period.

ARTHUR WILLIAM HARRIES.
